UNITED STATES PATENT OFFICE

FRANCISCO CLARK, OF DURANGO, MEXICO.

COMBINATION-KEY.

1,353,722.

Specification of Letters Patent. Patented Sept. 21, 1920.

Application filed June 17, 1919. Serial No. 304,888.

To all whom it may concern:

Be it known that I, FRANCISCO CLARK, a citizen of Mexico, and a resident of Durango city, in the State of Durango and Republic of Mexico, have invented a new and Improved Combination-Key, of which the following is a full, clear, and exact description.

This invention relates generally to a new and improved combination key and is more particularly adapted for use in combination with a lock which may be set to correspond with the setting of the combination key.

It is understood that it is not new broadly to provide a combination key *per se*. It is understood that heretofore certain patents have been granted on combination keys, but such constructions have embodied a complex and cumbersome arrangement of parts for actuating the tumbler mechanism within the lock, and again in the constructions heretofore suggested the positioning fingers or wards for actuating the tumblers within the lock have projected or extended laterally of the main key body and have generally necessitated a turning movement of the key.

A further objection to the constructions heretofore suggested is that if dirt and other particles become lodged in the keyhole, the lock is rendered inoperative and it is extremely difficult, if not impossible, to dislodge or clean the material therefrom in order that the key may be inserted therein. Under such circumstances, it is usually necessary to disassemble the entire locking mechanism to clean the same.

Further in combination keys heretofore suggested in order that a different combination may be obtained, it has necessitated the use of wards of a different shape or size.

One of the objects of this invention is to provide a key of simple construction, inexpensive to manufacture and to overcome the difficulties in combination keys of the construction above noted.

Another object is to provide in a combination key, a construction in which the various wards are of substantially the same construction, there being provided an adjusting means whereby the relative effective functioning parts thereof may be readily and

conveniently varied and adjusted throughout a wide range of settings.

Still another object of this invention is to provide a key having the ward elements slidable longitudinally of the main key body and having the ends of the various elements extending from the end of the key body so that it is only necessary to insert the end of the key in the keyhole of a lock without further movement thereof in order to release the locking mechanism and permit the bolt or latch to be withdrawn.

Still another object of this invention is to provide a combination key having a means therefor which maintains the said key in the keyhole against a spring pressure, in which position the said key holds the mechanism of the lock in such a position as to permit the free movement of the bolt or latch of the lock.

Still another object of this invention is to provide a combination key so constructed that it is only necessary to remember a certain series of numbers which corresponds to the particular setting of the wards or fingers of the key relative to a given lock, so that the setting thereof may be conveniently and readily changed to prevent unauthorized persons from effectively using the key, if lost, or any other master key to release the lock. On the other hand, if a key is lost, it would be unnecessary for the person having knowledge of the previous setting of the lost key to obtain a special key for his lock, it being only necessary that he obtain the temporary use of another key, perhaps of his neighbor having a similar type lock, and reset the fingers or wards to correspond with the setting of the tumblers in his particular lock.

The above objects are accomplished by providing, in the preferred form, a key having a main body and a plurality of fingers or wards, preferably of uniform construction, slidable longitudinally therein, and having the ends thereof projecting from the end of the main body of the key, there being provided a means whereby the distance, which the ends of the separate fingers or wards project beyond the ends of the key body, may be independently varied or adjusted.

Other objects and advantages will be apparent from the following description and the accompanying drawings. Similar characters of reference designate like parts in the several views.

In the drawings showing one of the preferred forms of the invention—

Figure 1 is a top plan view of a key embodying the invention;

10 Fig. 2 is a bottom plan view of Fig. 1;

Fig. 3 is a front elevation of Fig. 1;

15 Fig. 4 is a front elevation of one of the fingers;

Fig. 5 is a top plan view of Fig. 4;

20 Fig. 6 is a perspective view of the key embodying a preferred construction, showing one of the methods which may be conveniently used to vary the length of the projecting portion of the fingers beyond the end of the key body;

Fig. 7 is a broken sectional view of a portion of a combination lock showing the combination key positioned and held in the keyhole of said lock.

25 In the drawings showing one of the preferred forms of this invention, the key comprises a main body 1, which preferably is rectangular in form and having a suitable handle 2 in the form of a ring at one end thereof. The key body 1 is provided with an opening at one end thereof and a passageway extending inwardly of the body therefrom, there being provided ward or finger members 3, 4, 5, 6 and 7, having one end thereof extending within said passageway so that they may be independently moved longitudinally of the key body. It is understood that any suitable number of ward members may be employed.

40 There is provided a means for changing the relative lengths of the projecting end portions of the wards, there being provided for this purpose, in the preferred form, a plurality of spring fingers 9, 10, 11, 12 and 45 13, each of said spring members having a projecting portion 14 at the end thereof, which are positioned in slots 15 formed on one side of the wards. The spring fingers are preferably formed so that there will be an integral connection at one end thereof, such a construction being obtained by providing a strip of spring material 16 and securing one end thereof to the key body by a rivet connection 17 or other suitable means.

50 In order to form the spring fingers, longitudinal slits 18 are formed in said strip which extend inwardly from the end engaging the slotted portion of the wards, the end of each of the spring members being bent 55 downwardly as shown at 14 to engage the slots 15 of the wards. In the preferred construction shown, the bent portion 14 of the spring fingers is positioned substantially at the end of the key body 1. The end of each 60 of the ward members is provided with a

beveled surface 19, the purpose of which will later be seen.

The key, when used, will be inserted within the keyhole 23 and the end of the ward members will engage spring pressed tumblers 70 26 and the key will be held in such a position against the spring pressure 27 acting through the tumblers until the bolt 29 is released, this being accomplished without any further movement of the key. 75

As a means of holding the key within the keyhole against the spring pressure, there is provided on the key body a projecting lip 20, the said lip engaging a slotted opening 28 in the keyhole of the lock so that the key 80 may be held in its proper functioning position.

It is to be noted, in the preferred form, that the said projecting portion 20 is extended beyond the end of the main body 1 85 of the key, this construction being necessary because the said projecting lip 20 is inserted within the keyhole 23 while the end 21 of the main body portion of the lock is carried substantially flush with the outer edge 90 24 of the keyhole. The outer end 25 of the spring actuated tumblers 26 of the lock is provided with a surface tapered to correspond with the end of the ward members. It is further to be noted that the tapered 95 end 19 of the ward members is in such a direction that a pressure applied thereto would tend to keep the projecting lip 20 positioned within the recess.

For a more detailed description of a preferred form of a lock construction, which is particularly adapted for use with the key described herein, reference may be had to a patent application for the said lock, which is to be the subject of a separate patent. 100

105 There is provided as a means in order to facilitate the adjustment of the lengths of the projecting ends of the various ward members, an opening 22 between the finger members adjacent the end thereof, so that the end of a pin 23' may readily be inserted therein to raise the finger until the bent end portion 14 thereof is out of engagement with the slot 15, at which time the ward may be moved to a desired position relative to the 110 other ward members and to correspond with the setting of the coacting tumbler member within the lock. 115

120 It is to be noted that all of the ward members, irrespective of the number used, may be uniform or identical, it being only necessary that an adjusting means be provided to vary the length of the projecting parts thereof which are inserted within the keyhole of the lock to actuate coöperating 125 tumbler elements therein.

Further, if it is desired, after a door has been locked, it is only necessary to change the setting of any one or any number of the ward members in order to make it im- 130

possible for an unauthorized person to use the key if lost.

Another important feature, in the use of such a combination key construction, is that it makes impossible the use of a master key to actuate the tumblers of a lock.

Of course, if a person has a combination key of this type and knows the combination of a key which corresponds with the setting of the tumblers of a particular lock, any key of this particular type may be readily reset to that combination. However, the combination of a lock, designed to be used with a combination key of this type, which is the subject of a separate patent application, may be readily and conveniently changed so as to make it impossible for the lock to be opened by using the old combination.

While the drawings, embodying a preferred form, show but five ward members and five slots therein to permit the adjustment thereof, it is understood that any desired number of wards may be used and any desired number of slots may be provided therein. The number of slots will correspond to the number of pins or pegs used to secure a particular combination in the setting of the tumblers of the locks.

The number corresponding to the particular combination of the key will be represented by the slot in which the spring finger is positioned. For example, in Fig. 1, the setting of the ward members would correspond to the combination represented by the number 42434, and the setting of the ward members in Fig. 6 would correspond to the combination represented by the number 42134. In the above last-mentioned number where 4 is used, it means that the bent end portion of the spring is positioned in the fourth slot of the first ward. The bent end portion of the second spring member is positioned in the second slot of the second ward member, and the number 1 meaning that the end of the middle or third spring finger member is positioned in the first slot of the middle or third ward member.

There has been shown herein but one preferred form of construction, but it is understood that various changes and modifications thereof may be made without departing from the spirit and scope of this invention.

Having thus described the invention, what I claim as new is:

1. A combination key comprising a main body, a plurality of fingers of identical construction movable longitudinally of the key body and independently of each other and having the ends thereof beveled extending beyond the end of the key body, means for independently positioning each of said fingers, means including a bent lip portion for holding the said key in a key hole.

2. A combination key comprising a main body, a plurality of fingers of identical construction movable longitudinally of the key body and independently of each other and having the ends thereof extending beyond the end of the key body, means for independently positioning each of said fingers, and a lip extending laterally from the body for holding said key in the keyhole against a spring pressure, the ends of the fingers being beveled on the side opposite said lip to make more effective the action of the lip.

3. A combination key comprising a key body, and a plurality of wards slidable longitudinally and having the ends thereof extending beyond the body of the key, the side of one of the said ward members having a series of slots adapted to align with the end of the key body to serve as indicating marks, the end of the key including bent finger portions adapted to engage the slots, and a means including a projecting portion for holding the key in the key hole.

4. In a combination key, a key body, a ward slidable longitudinally therein and having the end thereof tapered and extending beyond the end of the key body, said ward having slots adapted to serve as indicating means, and means for varying the distance to which said ward extends beyond the end of said body, said means including a spring finger having a bent portion forming the edge of a key and adapted to engage the slots to prevent movement of the ward in either direction.

5. In a combination key, a key body, a ward member slidable longitudinally therein and having the end thereof extending beyond the end of the key body, said ward having a notched surface thereon, means for varying the distance which said ward extends beyond the end of said key body, said means including a member yieldingly engaging the notched surface of said ward, to prevent movement in either direction and means arranged forward of the end of the key body to hold the key in the key hole.

6. A combination key comprising a key body, a plurality of finger members slidable longitudinally thereof and the ends thereof being tapered and projecting beyond the end of said key body, each of said finger members having a notched surface, and a plurality of resilient members carried by the key body and having projecting portions to engage the notched surfaces of the finger members to prevent movement thereof in either direction, the resilient members forming one side of the key body and a covering for the finger members.

7. A combination key comprising a key body having a longitudinal passage extending inward of the key from one end thereof, ward members slidable within said passage and having the ends tapered and projecting

beyond said key body, a means including a plurality of spring finger members for independently varying the length of the projecting end portions of the ward members, 5 and means including a lip portion forward of the end of the key for holding the key within the key hole.

8. A combination key, comprising a key body, a plurality of finger members slidable 10 longitudinally thereof and having the ends extending beyond the main key body, and means to hold said key in a keyhole against a spring pressure, said means including a projecting lip portion on said key body.

15 9. A combination key comprising a body, ward members having the ends thereof projecting beyond the end of the body, each ward member having a beveled surface at its functioning end, and means for holding 20 the key in a keyhole, said means comprising an outwardly bent lip portion forward of the end of the key body.

10. A combination key, adapted to release 25 a locking mechanism by being positioned within a keyhole without further movement, comprising a body and ward members having the ends thereof extending longitudinally beyond said body, the said projecting ends being beveled and adapted to be inserted 30 within the keyhole, and a means projecting from the key body on the side opposite to

the beveled surface of the ward to hold the key in the key hole.

11. A combination key, adapted to release 35 a locking mechanism by being positioned within a keyhole without further movement, comprising a body, ward members having the ends thereof extending longitudinally beyond said body, the said projecting ends being adapted to be inserted within the keyhole, and a means carried by the key to hold 40 said key in the keyhole of a lock.

12. A combination key comprising a key body open at one end and one side thereof, 45 a closure for said opened side, including a plurality of spring fingers, having bent end portions forming a partial closure for the open end, openings for the finger portions, through which a pointed instrument may be inserted to raise said fingers, a plurality of 50 ward members, adapted to slide within the key body, and having an end extending from the key body, each of said ward members having a plurality of slots therein adapted to receive the bent end of the spring 55 fingers whereby the said ward members are held against movement in either direction, the slotted portion serving as visible indicating marks, and a means carried by the key for holding the said key in a key hole. 60

FRANCISCO CLARK.
